INVENTOR.

John F. Kerr

UNITED STATES PATENT OFFICE.

JOHN F. KERR, OF PATERSON, NEW JERSEY.

TROLLEY.

SPECIFICATION forming part of Letters Patent No. 710,469, dated October 7, 1902.

Application filed August 8, 1901. Serial No. 71,300. (No model.)

To all whom it may concern:

Be it known that I, JOHN F. KERR, a citizen of the United States, residing at 171 Hamilton avenue, city of Paterson, in the county of Passaic and State of New Jersey, have invented certain new and useful Improvements in Trolleys, of which the following is a specification, reference being had therein to the accompanying drawings.

My invention relates to trolleys for electric-railway cars, and has for one object to provide improved means for securing the trolley-wheel against displacement from the line-wire while the car is running.

A further object is to provide a device of this character which can be readily attached to the trolley-poles as now in ordinary use without the requirement of structural alteration.

A still further object is to enable the trolley-wheel to swerve readily as required to either side of the line of draft when turning a curve and to permit the wheel-support to be depressed and raised vertically when necessary and to control the swerving of the trolley-wheel, so that it will keep in its normal position or in alinement with the wire when not turning around a curve.

The accompanying drawings form a part of this specification and represent what I consider the best means of carrying out the invention.

Figure 1 is a side elevation, partly sectional. Fig. 2 is a front view, and Fig. 3 is a side elevation, of my invention slightly modified.

Similar letters of reference indicate like parts in all the figures where they appear.

A is a trolley-head which comprises the body portion A', the shank A² for securing to the pole the lug A³, and a plug or plate-cap A⁴.

B is a swivel-head adapted to turn in the body portion A' and provided with a fork or clevis B', into which the trolley-wheel C turns on the pivot or bolt C'. The groove or trough 45 in the trolley-wheel C is peculiarly formed, as is shown in Fig. 2, the bed or bottom of the trough being curved where it receives and contacts with the line-wire. The curved bottom of the trough is broken on both sides by 50 an abrupt flat annular bearing-surface rising vertically at right angles to the axis of the wheel, which vertically-extending annular

face is adapted to guide and control the wheel as it presents a resisting-surface to the wire which turns the swivel-head in rounding a curve.

The spindle B⁴ of the swivel-head B passes downwardly through the center of the body portion A' and through the plate-cap A⁴ and is secured therein by means of the washer B⁶ and the securing-nut B⁵. A tube E', having on its upper end a plate E adapted for ball-bearings, fits loosely around the spindle B⁴ in the body portion A' and together with the lower portion B³ of the swivel-head B forms an annular ball-race for the spherical balls f.

On the swivel-head B is formed a clevis B², normally at right angles to the body portion A', in which the free end of the spring D is held. The lower end of the spring D is secured by a rivet D' in the lug A³ on the body portion A'. The spring D is thus securely held in a vertical position, the lower end thereof being secured to the body portion A' and the upper or free end thereof being held in the clevis B² of the swivel-head B.

Around the tube E', which surrounds the spindle B⁴, is located the helical spring F, the upper portion of the spring bearing against the under side of the plate E and the lower end of the spring resting and bearing on the plug or plate-cap A⁴. This spring permits the slight required elevation and depression of the swivel-head B in the body portion A'.

The ball-bearings render the operation of the swivel-head B easy, and the spring D permits and controls the swerving of swivel-head B when the wheel is rounding a curve and then causes the swivel-head and the trolley-wheel, which is carried in the rearwardly and upwardly extending support and clevis B', to return to its normal position in alinement with the line-wire. The spring F tends to keep the trolley C in contact with the wire.

In Fig. 3 my invention is shown slightly modified. In Fig. 3 the swivel-head B turns on the stationary non-rotatable spindle K, which is secured therein by means of a nut K', and a clevis B³¹ is formed on the rearwardly and upwardly extending clevis portion, the spring D being secured to a lug A⁵, forming a part of the body portion A', and the upper or free end of the spring being held in said clevis B³¹.

The fork is always upright when the trolley-pole is at its usual angle for working.

Parts of the invention can be used without the whole.

5 Modifications may be made without departing from the principles or sacrificing the advantages of the invention.

I claim—

1. A trolley-head, having a vertical tubular body portion and a lug integral therewith and a shank also integral therewith for securing to the pole, in combination with a swivel-head adapted to turn in said tubular body portion of the trolley-head, and having a rearwardly and upwardly extending fork and a forwardly extending clevis both integral therewith, a trolley-wheel mounted to rotate in said fork at a point back of the center of said swivel-head, and a spring, the lower end of which is secured to said lug on the trolley-head, and the upper or free end thereof extending through the clevis on the swivel-head, substantially as set forth.

2. In a trolley, a trolley-head having a vertical tubular body portion, in combination with a swivel-head having a rearwardly and upwardly extending fork integral therewith, a wheel mounted to turn in said fork at a point back of the turning-point of the swivel-head, a vertical spindle for said swivel-head extending through the tubular portion of the trolley-head, a tube surrounding said spindle and having an annular plate secured to its upper end, the upper surface of said plate and the bottom of said swivel-head forming an annular ball-race around said spindle, spherical balls located therein, a plug suitably secured in the lower end of said tubular portion of the trolley-head, a helical spring surrounding said tube inside of the trolley-head, the upper end of the spring bearing against the under side of the plate on said tube, and the lower end of the spring resting and bearing on said plug, and means to permit and control the turning of said swivel-head, substantially as set forth.

3. In a trolley, a trolley-head having a vertical tubular body portion, in combination with a swivel-head having a rearwardly and upwardly extending fork integral therewith, a wheel mounted to turn in said fork at a point back of the turning-point of the swivel-head, a vertical spindle for said swivel-head extending through the tubular portion of the trolley-head, a tube surrounding said spindle and having an annular plate secured to its upper end, the upper surface of said plate and the bottom of said swivel-head forming an annular ball-race around said spindle, spherical balls located therein, a plug suitably secured in the lower end of said tubular portion of the trolley-head, a helical spring surrounding said tube inside of the trolley-head, the upper end of the spring bearing against the under side of the plate on said tube, and the lower end of the spring resting and bearing on said plug, and means to permit and control the turning of said swivel-head, substantially as set forth.

bearing against the under side of the plate on said tube, and the lower end of the spring resting and bearing on said plug, substantially as set forth.

4. In a trolley, a trolley-head having a vertical tubular body portion, in combination with a swivel-head having a rearwardly and upwardly extending fork integral therewith, a wheel mounted to turn in said fork at a point back of the turning-point of the swivel-head, a vertical spindle for said swivel-head extending through the tubular portion of the trolley-head, a tube surrounding said spindle and having an annular plate secured to its upper end, the upper surface of said plate and the bottom of said swivel-head forming an annular ball-race around said spindle, spherical balls located therein, a plug suitably secured in the lower end of said tubular portion of the trolley-head, a helical spring surrounding said tube inside of the trolley-head, the upper end of the spring bearing against the under side of the plate on said tube, and the lower end of the spring resting and bearing on said plug, and means to permit and control the turning of said swivel-head, substantially as set forth.

5. The combination with the swivel-head, having a trailing-wheel mounted thereon, and a vertical spindle, of the trolley-head, a tube therein through which said spindle passes, an expansion-spring surrounding said tube, and means for controlling the movement of said swivel-head in a horizontal plane, substantially as set forth.

In testimony whereof I affix my signature in presence of two witnesses.

JOHN F. KERR.
